UNITED STATES PATENT OFFICE

JOHN JELLIFF PLATT, OF MILFORD, CONNECTICUT.

SPARK-PLUG.

1,088,620.

Specification of Letters Patent.

Patented Feb. 24, 1914.

Application filed May 24, 1912. Serial No. 699,432.

To all whom it may concern:

Be it known that I, JOHN J. PLATT, a citizen of the United States, residing at Milford, in the county of New Haven and 5 State of Connecticut, have invented new and useful Improvements in Spark-Plugs, of which the following is a specification.

This invention has relation to spark plugs intended chiefly for internal combustion engines embodying an electric ignition system, the purpose being the provision of a spark plug of the breech-block type and to combine therewith means whereby the engine may be primed to facilitate the starting 10 thereof and to admit of the flash due to the passage of the spark and to the ignition of the gaseous mixture being readily observed so that it may be instantly determined whether the spark is passing or the gaseous 15 mixture exploding.

The invention aims further to provide a spark plug having tubular electrodes which may be utilized as means for conveying the fuel to the engine when priming the same 20 or for conveying the flash incident to explosion of the gaseous mixture to a predetermined point for observation or to admit of the introduction of a cleaner whereby the space between the electrodes may be 25 cleared of any carbon or other obstructing matter or which may be used as a blow-off for carrying away any matter tending to foul the electrodes by providing an escape for the 30 air or gaseous mixture on the compression 35 stroke of the piston.

The invention further contemplates novel means for closing the circuit to prevent the formation of a spark during the time that fuel is supplied to the engine for priming 40 the same, with the result of preventing premature explosion.

The invention further proposes to combine with a spark plug means whereby the circuit may be interrupted to admit of the 45 spark being observed provided the ignition system is in proper working condition so that any cylinder of a multiple engine missing by reason of failure of the spark may be quickly determined, with the result that 50 the difficulty being located may be quickly remedied.

The invention also contemplates novel means for priming the engine, said means being readily accessible to be operated on 55 a moment's notice to admit of supplying gasoline or other liquid fuel to the engine

for priming the same when the engine is difficult of starting, as in cold weather.

The invention consists of the novel features, details of construction and combination of parts, which hereinafter will be more particularly set forth, illustrated in the accompanying drawings, and pointed out in the appended claims.

Referring to the drawings, forming a part 65 of the specification, Figure 1 is a vertical central section of a spark plug embodying the invention. Fig. 2 is a side view of the shell or bushing which is adapted to be fitted to the cylinder of the engine. Fig. 70 3 is a sectional detail of the shell forming one member of the breech-block between the two parts of the spark plug. Fig. 4 is a detail view in perspective of the spark gap body having the switch in position by 75 means of which the electric circuit may be broken to admit of observing the spark. Fig. 5 is a horizontal section on the line 80 $x-x$ of Fig. 1. Fig. 6 is a horizontal section on the line $y-y$ of Fig. 1.

Corresponding and like parts are referred to in the following description, and indicated in all the views of the drawings, by the same reference characters.

The spark plug illustrated is of the 85 breech-block type and comprises two parts which are readily separable by means of a partial rotation of one of such parts.

The part to be attached to the cylinder 90 of the engine is indicated at 41 and consists of a shell or bushing. The lower end of the shell 41 is threaded to admit of its screwing into a threaded opening formed in a part of the engine. The upper part of the shell 41 is formed upon its outer side with 95 screwthread sections 37, which are adapted to engage with screwthread sections 37^a upon the inner side of a shell 36; thereby forming the breech-block between the two parts of the spark plug. The screwthread 100 sections 37 are separated by plain portions of such a width as to receive the screwthread sections 37^a of the shell 36, thereby admitting of slipping of one shell upon the other when the screwthread sections of one 105 are brought opposite the plain portion between the screwthread sections of the other. After the shells 36 and 41 have been brought together they are locked by a relative turning of one upon the other which brings the 110 screwthread sections 37 and 37^a into engagement, said screwthread serving to draw the

parts together so as to insure the formation of a close joint between the parts. The opening in the lower portion of the shell 41 is straight, whereas the opening in the upper portion of the shell is flared to receive a tapered part 36^a of the shell 36. A cross bar T is provided at the lower end of the shell 41 and is provided at a central point with a threaded opening in which is fitted the negative electrode 39. The electrode 39 is tubular and its lower portion is threaded, thereby admitting of the electrode being adjusted vertically with reference to the cross bar to regulate the space between the positive and the negative electrodes. A jam nut 38 threaded upon the lower portion of the electrode 39 secures the latter in the adjusted position. The electrode 39 may be adjusted by means of a screwdriver or other instrument fitted into a slot formed in the lower end of the electrode after the jam nut 38 has been loosened.

The upper or detachable part of the spark plug comprises the shell 36, which is formed with a tapered portion 36^a of such a size and taper as to fit within the tapered opening in the upper part of the shell 41. The shell 36 has its upper portion externally threaded to receive a lock nut 35 and has an angular portion 36^b at the base of the upper threaded portion to receive a handle by means of which the upper part of the spark plug is turned when making or breaking the breech-block. The inner end of the handle 42 has an angular opening to receive the angular part 36^b and is confined between the lock nut 35 and the shoulder formed at the base of the angular portion 36^b. The tapered part 36^a of the shell 36 has its lower end contracted to form an inner shoulder 36^c, which engages and supports a body 32 of insulating material, such as porcelain or other vitreous material. A gland 33 is threaded into the upper portion of the shell 36 and secures the body 32 therein.

The handle 42 has its outer portion hollow and is closed at its outer end by means of a cap 43. The space within the handle is intended chiefly to contain a cleaner 44 by means of which the electrodes and the space between the electrodes may be cleared of any obstructing matter. Obviously terminals or other small sundry articles may be placed in the space of the handle to be conveniently at hand when required for use.

The body 32 of insulating material is formed with a central opening and its lower end is reduced to enter the opening formed in the lower portion of the shell 41. The opening 32^a formed in the lower portion of the body 32 is of greater diameter than the opening formed in the upper portion and is adapted to receive the ends of the two electrodes and the lower enlarged portion of the upper or high tension electrode 50. The

middle portion of the body 32 is slightly enlarged to form upper and lower shoulders, the latter engaging the shoulder 36^a and the gland 33 engaging the upper shoulder.

The high tension electrode 50 is tubular and its lower portion is enlarged and is fitted within the enlarged opening 32^a. The electrode 50 is of a length to project some distance beyond the end of the body 32, the projecting portion being externally threaded. A ferrule 30 is fitted upon the upper end of the body 32 and is threaded on the projecting end of the electrode 50. A plate 29 is fitted on the projecting end of the electrode 50 and is clamped between the ferrule 30 and a lock nut 22. A fitting 26 is threaded upon the projecting end of the electrode 50 and its lower end engages the lock nut 22. The upper portion of the fitting 26 is recessed to receive a short section 27 of glass tubing, the sides of the recessed portion having observation openings to admit of the flash resulting from combustion of the gaseous mixture being seen. The fitting 26 is of metal and its lower portion is externally threaded to receive a bushing 51, which has an outer flange at its lower end to receive and support the spark gap body 21. A nut 20 is threaded upon the fitting 26 and extends over the body 21 and is formed with openings 21^a to admit of the spark being readily seen when the circuit is interrupted by means of the switch. The upper end of the fitting 26 is threaded to receive a cup 12. 100 Packing 17 and 19 is interposed between the ends of the glass tube 27 and the parts 12 and 26 to insure the formation of a tight joint.

The spark gap body 21 is constructed of insulating material, such as compressed paper, vulcanized rubber or other tough and non-combustible material. The body 21 is fitted upon the bushing 51 and has an annular groove 52 in which is fitted a metal washer 24 and is adapted to receive the terminal of the high tension wire. The upper portion of the body 21 has a recess 25 in which is arranged a switch 22 having an insulated handle. A contact P is fitted in a part of the body separating the annular groove 52 from the recess 25 and is in electrical connection with the washer 24. The switch 22 is adapted to close the circuit through the contact P and when moved to a position to interrupt the circuit results in the formation of a gap across which the spark jumps, thereby admitting of said spark being observed through the openings 21^a of the part 20. The wall of the body 21 surrounding the recess 25 has a slot 21^b through which a part of the switch 22^a extends.

The cup 12 consists of a fitting having recesses in the opposite ends and a centrally 130

disposed opening establishing communication between said recesses, the lower end of the opening being enlarged to form a seat 12^a for a valve 12^b, which is adapted to open 5 downwardly and has its stem projecting into the upper recess and receiving a spring 13 by means of which the valve is seated and normally held closed. The stem of the valve 12^b fits loosely within the opening formed 10 in the lower part separating the recesses formed in the ends of the cup 12 so that when the valve is unseated a passage is had between the recessed ends of the part 12. A cap 6 is threaded to the upper end of the 15 part 12 and closes the recess thereof. A tube 11 connects with the cap 6 and leads into the recess 14 in the upper end of the part 12 so as to convey gasoline or other liquid fuel thereto. A stem 1 is mounted 20 in the cap 6 in line with the valve 12^b and is pressed outwardly by means of a spring 5 interposed between a nut 3 mounted upon the stem 1 and a tubular extension of the cap 6. A plate 4 is mounted upon the stem 25 1 and is clamped thereto between the nut 3 and a companion nut 2. A rod 16 is mounted in the parts 4, 6 and 29 in such a manner as to move therein. The lower end of the rod 16 is adapted to make electric connection with the lower part of the spark plug, thereby closing the circuit between the two electrodes and preventing the passage of the spark at such times when the valve 12^b is unseated. The rod 16 passes loosely 30 through the plate 4 and receives a nut N upon its upper portion above the plate 4 and a spring 9 below said plate, said spring being supported at its lower end upon a stop 10. When the stem 1 is pressed inward to 40 unseat the valve 12^b it at the same time moves the rod 16, thereby bringing it in contact with the lock nut 35 or breech part of the plug so as to close the circuit and thereby prevent the spark between the electrodes 45 50 and 39. The spring 9 forms a yielding connection between the part 4 and the rod 16, thereby admitting of the stem 1 continuing to move after the rod 16 has come in contact with the lock nut 35.

50 The tube 11 connects with any suitable source for supplying gasoline or other liquid fuel whereby the engine may be primed when required. When the space 14 is supplied with gasoline or liquid fuel the latter may 55 pass into the engine through the tubular electrodes 50 and 39 when the valve 12^a is unseated, this being accomplished by pressing inward upon the stem 1. At or an instant before the valve 12^b is unseated the 60 circuit is closed by means of the rod 16 coming in contact with the lock nut 35, thereby preventing the formation of a spark. The stem 1 may be operated in any manner, as by means of a shaft 53 and a cam 54, the 65 latter forming a part of or secured to the

shaft 53. When the shaft 53 is turned the cam 54 coming in contact with the stem 1 presses the same inward and unseats the valve 12^b, thereby permitting the liquid fuel to pass from the recess 14 through the electrodes 50 and 39 into the cylinder of the engine. 70

The electrodes 50 and 39 may be formed of metal tubing of any nature and may be provided with tips of German silver, platinum or other material best adapted to form spark terminals. The flash resulting from combustion of the gaseous mixture may be seen in the part 27, thereby apprising the operator that the engine is working properly. The flash is conveyed to the part 27 through the tubular electrodes. The spark passing between the terminals of the electrodes may likewise be observed by looking downwardly through the electrodes after 80 uncovering the upper end of the part 26, either by removing the cup 12 or an equivalent part to the upper end of the fitting 26.

The construction is such as to admit of a cleaner being passed through the electrodes 90 to remove any soot or other fouling matter therefrom. The cleaner 44 may consist of a slender brush embodying a wire stem and bristles fitted to an end thereof. This cleaner when passed through the electrodes will remove any matter lodging between the terminals of the electrodes without necessitating the separation of the upper part of the spark plug from the part attached to the cylinder of the engine. 95

When the valve 12^b is unseated and the engine is operated the gaseous mixture may be forced from the cylinder upon the compression stroke of the piston so as to pass through the electrodes and carry off all obstructing matter. If preferred the valve 12^b 105 may be unseated when the gaseous mixture is compressed in the cylinder, thereby affording a quick relief through which the gaseous mixture escapes with a great rush, thereby 110 serving to clear the electrodes of any fouling matter.

The working of the ignition system may be determined by looking downwardly 115 through the electrode 50 or by moving the switch 22^a to form a spark gap in the recess 25 of the body 21 so that the spark may be observed through the openings 21^a of the lock washer 20.

It is to be understood that the tubular 120 electrodes and the spark and flash sight, as also the priming mechanism may be applied to spark plugs of any variety, whether of the breech-block type or other form.

From the foregoing description, taken in 125 connection with the accompanying drawings, the advantages of the construction and of the method of operation will be readily apparent to those skilled in the art to which the invention appertains, and while I have 130

described the principle of operation of the invention, together with the device which I now consider to be the best embodiment thereof, I desire to have it understood that 5 the device shown is merely illustrative, and that such changes may be made when desired as are within the scope of the claims appended hereto.

Having thus described the invention what 10 is claimed as new, is:—

1. In a spark plug the combination of a body, electrodes at the lower end of the body, the upper electrode being tubular and extending above the said body, a fitting 15 connected with the upper projecting end of the electrode and having a recess in its upper end and an observation opening in its side leading into said recess, and a tube of transparent material secured in the recess

20 of the fitting and in communication with the tubular electrode to admit of fuel passing therethrough and the spark or flash due to ignition being viewed through the lateral observation opening.

25 2. In a spark plug the combination of a body, electrodes carried by the body, the upper electrode being tubular and projecting through and above the body, a fitting attached to the projecting end of the electrode and having a recess in its upper end and an observation opening in a side leading into the recess, a tube of transparent material secured in the recess of the fitting and in communication with the tubular 30 electrode, a cup attached to the upper end of the fitting and securing the sleeve therein, and a valve closing an opening in the bottom of said cup.

3. In a spark plug the combination of a 40 body, electrodes carried by the body, the upper electrode being tubular and projecting through and above the body, a fitting attached to the projecting end of the electrode and having a recess in its upper end and an observation opening in a side leading into the recess, a tube of transparent material secured in the recess of the fitting and in communication with the tubular electrode, a cup attached to the upper end 45 of the fitting and securing the sleeve therein, a valve closing an opening in the bottom of said cup, a cap for closing the cup, a stem slidably mounted in the cap in line with the valve, and a rod having connection with the stem and adapted to short circuit the electrodes preliminary to the unseating of the valve.

4. In a spark plug the combination of a 50 body, electrodes carried by the body, the upper electrode being tubular and projecting through and above the body, a fitting attached to the projecting end of the electrode and having a recess in its upper end and an observation opening in a side leading into the recess, a tube of transparent material secured in the recess of the fitting and in communication with the tubular electrode, a cup attached to the upper end 55 of the fitting and securing the sleeve therein, a valve closing an opening in the bottom of said cup, a cap for closing the cup, a stem slidably mounted in the cap in line with the valve, and a rod having connection with the stem and adapted to short circuit the electrodes preliminary to the unseating of the valve.

4. In a spark plug the combination of a 60 body, electrodes carried by the body, the upper electrode being tubular and projecting through and above the body, a fitting attached to the projecting end of the electrode and having a recess in its upper end and an observation opening in a side leading into the recess, a tube of transparent material secured in the recess of the fitting and in communication with the tubular electrode, a cup attached to the upper end of the fitting and securing the sleeve therein, a valve closing an opening in the bottom of said cup, a cap for closing the cup, a stem slidably mounted in the cap in line with the valve, and a rod having connection with the stem and adapted to short circuit the electrodes preliminary to the unseating of the valve.

trode and having a recess in its upper end and an observation opening in a side leading into the recess, a tube of transparent 65 material secured in the recess of the fitting and in communication with the tubular electrode, a cup attached to the upper end of the fitting and securing the sleeve therein, a valve closing an opening in the bottom of said cup, a cap for closing the cup, a stem slidably mounted in the cap in line with the valve, a rod for short circuiting the electrodes, and a yieldable connection between said rod and stem to admit of the 70 continued movement of the latter after the rod has ceased movement after short circuiting the electrodes.

5. In a spark plug the combination of a body, electrodes supported by the body, the upper electrode being tubular, a cup connected with the body and having an opening in its bottom, a valve for closing the opening of the cup, a cap for closing the cup, a spring actuated stem mounted in the 80 cap and adapted when depressed to unseat the valve, a rod for short circuiting the electrodes, and a yieldable connection between said rod and stem to admit of the latter having a continued movement after 90 the rod has ceased to move after short circuiting the electrodes.

6. In a spark plug the combination of a spark gap body of insulating material having a recess in its upper side, a fixed contact 95 having its respective ends exposed within the recess and upon the exterior of said body, the outer end being adapted to make electric connection with the conducting wire, and a switch arranged within the spark 100 gap body and having electric connection with one of the electrodes of the plug and adapted to make connection with the before mentioned contact.

7. In a spark plug the combination of a 105 spark gap body having its upper side formed with a recess and having a slot in the wall surrounding said recess, a fixed contact having its respective ends exposed within the recess and upon the outside of the said body and adapted to have the conducting wire connected thereto, a switch co-operating with the fixed contact fitted within the recess of the spark gap body and having electric connection with one of the electrodes of the spark plug, and a handle for operating the switch passing through the slot in the side of said spark gap body.

In testimony whereof I affix my signature in presence of two witnesses.

JOHN JELLIFF PLATT.
